UNITED STATES PATENT OFFICE.

GEORGE H. GUTHRIE, OF ST. MARYS, OHIO, ASSIGNOR TO MUNCIE GAS ENGINE AND SUPPLY COMPANY, OF MUNCIE, INDIANA, A CORPORATION OF INDIANA.

DRIVE-HEAD FOR CASINGS FOR GAS, OIL, OR OTHER WELLS.

SPECIFICATION forming part of Letters Patent No. 710,860, dated October 7, 1902.

Application filed July 18, 1901. Serial No. 68,829. (No model.)

To all whom it may concern:

Be it known that I, GEORGE H. GUTHRIE, a citizen of the United States, residing at St. Marys, in the county of Auglaize and State of Ohio, have invented new and useful Improvements in Drive-Heads for Casings for Gas, Oil, or other Wells, of which the following is a specification.

This invention relates to certain new and useful improvements in drive-heads for drive-pipes and casings for oil, gas, or other wells.

The invention aims to construct a drive-head which may be termed a "drop" drive-head for oil and gas well drive-pipes and casings and aims to overcome the destroying of the threads on the casing-section and coupling. The devices which are generally used for this purpose in connection with oil-well casings are provided with threads, on which is screwed the coupling for connecting the casing-sections together, the objection to drive-heads of this character being that any amount of inconvenience is caused by the destroying of the threads both on the casing-section and the coupling.

The object of this invention is to provide a head used in connection with oil-well casings which will drop inside the casing and rest on the top of the coupling.

The invention further aims to construct a drive-head with an elongated shank, so that when in position it will remain in the casing-section and not injure the same nor the threads of the coupling.

The invention further aims to construct a drop drive-head for oil and gas well drive-pipes and casings which shall be extremely simple in its construction, strong, durable, efficient in its use, comparatively inexpensive to manufacture; and to this end it consists in the novel combination and arrangement of parts hereinafter more specifically described, illustrated in the accompanying drawings, and particularly pointed out in the claim hereunto appended.

In describing the invention in detail reference is had to the accompanying drawings, forming a part of this specification, wherein like numerals of reference indicate corre-

sponding parts throughout the several views, 50 and wherein—

Figure 1 is a top plan view of my improved head. Fig. 2 is a vertical sectional view thereof; and Fig. 3 is a vertical sectional view of an oil-well casing, showing my improved head 55 attached thereto.

Referring to the drawings by reference-numerals, 1 indicates the upper section of an oil-well casing, which is exteriorly screw-threaded and has secured thereto the coupling 2, which projects above the same.

The reference-numeral 3 denotes the bit, and 4 the stem therefor, which extends upwardly through the drive-clamps 5 6, secured together by the bolts 7, and is usually attached 65 to the platform or derrick (not shown) when drilling oil-wells.

I have shown the foregoing, which forms no part of my invention, so that the arrangement of the drop drive-head in connection with the 70 casing-section and coupling can be understood.

The reference-numeral 8 denotes the body portion of the drive-head, which is substantially tubular and formed with a depending tubular shank 9, the head and shank being 75 hollow, with the external diameter of the depending shank less than the external diameter of the body portion. By forming the body and shank of two different diameters an annular shoulder 10 is formed at the juncture 80 thereof, which is adapted to rest upon the top edge of the coupling. The body portion is provided with openings 11 for the purpose of connecting a rope or other means thereto to fasten the head up to the stem, so as to keep 85 it out of the road when they are disconnecting the bit from the stem. The head is used by slipping it upon the stem. The bit is then secured to the latter, which is then inserted within the casing, and when the tool is pulled 90 up through the casing the tool, being larger than the depending shank, elevates the head out of the casing and leaves the top of the casing clear to run the sand-pump. When the tools are inserted in the casing, the head drops into place on the top of the coupling 95 and the depending shank extends within the coupling and casing, remains there and keeps

the rope from cutting on the sharp edge of the casing or threads of the coupling, and also protects the said threads from injury, as will be evident, during the boring operation.

5 It will not only be evident from the foregoing statement that the rope is kept from being cut on the sharp edge of the casing or threads of the coupling and that the threads of the coupling are protected from injury, 10 but it will also be evident that an immense amount of time and labor is saved by the employment of the drop drive-head constructed in the manner as hereinbefore set forth. The time saved is usually from twenty to 15 thirty minutes in adjusting the drive-head to each joint of pipe as it is driven in the well, as the screw drive-head has to be screwed on with large wrenches, which takes from twenty to thirty minutes at each operation, while by 20 the employment of the construction of the drive - head as hereinbefore set forth it is simply dropped in the end of the pipe or collar, or, in other words, it is not necessary for the drive-head to be screwed to the coupling 25 in any manner or to the pipe-section. This is a material advantage not possessed in the screw drive-heads usually employed.

It is thought that the many advantages of a drop drive-head for oil-well casings constructed in the manner set forth can be readily 30

understood from the foregoing description, taken in connection with the accompanying drawings, and it will also be noted that minor changes may be made in the details of construction without departing from the general 35 spirit of my invention.

Having thus fully described my invention, what I claim as new, and desire to secure by Letters Patent, is—

A drop drive-head for oil-well casings, consisting of a hollow body portion provided with a pair of openings for the purpose of connecting a suitable means thereto to fasten the drive-head for the purpose set forth, and an elongated hollow shank integral with said 45 body portion and having a smooth periphery, said shank of less diameter than said body portion, said body portion adapted to rest upon the upper end of the casing when the drive-head is in operative position and said 50 shank adapted to extend within and be freely removable from the casing when the body portion engages the top thereof.

In testimony whereof I have hereunto set my hand in presence of two subscribing witnesses. 55

GEORGE H. GUTHRIE.
